United States Patent Office.

FREDERICK W. PORTER, OF SPRINGFIELD, VERMONT.

Design No. 4,445, dated October 25, 1870.

DESIGN FOR A TOY-CARRIAGE.

The Schedule referred to in these Letters Patent and making part of the same

To all whom it may concern:

Be it known that I, FREDERICK W. PORTER, of Springfield, in the county of Windsor and State of Vermont, have invented and produced a new and original Design for a Toy-Carriage, of which the following is a specification.

My design relates to the form or shape of the body of a toy-carriage, and is fully shown in the accompanying photographic illustration and the letters marked thereon, to which reference is made.

The body extends up at the back part at *d*, and has a curved recess at *e*, and also extends upward at *A*, the two parts, *A* and *d*, being the highest parts of the body, the front end of which projection is cut off,

at an inclination, to support the foot-board, as shown at *h*.

The sides project forward at *a*.

A curved recess is made at *c*, and the bottom extends backward and upward by the curved line *c* to the top at *d*.

What I claim as my invention, is—

The design for a toy carriage-body, substantially as shown and described.

FREDERICK W. PORTER.
